UNITED STATES PATENT OFFICE

2,547,627

DEVICE FOR HANDLING BURIAL VAULTS

Henry C. Dreischerf, Chicago, Ill.

Application August 31, 1945, Serial No. 613,743

8 Claims. (Cl. 254—136)

1

This invention is concerned with a device for handling burial vaults.

The term "handling" is intended to cover the manipulating of heavy burial vaults, at cemeteries, from the place of receipt to the place of interment. The manipulations include raising such a vault, e. g., a concrete vault, which may weigh two tons or more, moving it safely to the place of interment within the cemetery, and finally depositing it at the place of interment. The final operation may require lowering of the vault into the ground.

Such vaults are now raised with jacks and pulleys, are placed on rollers, and are then manually rolled and pushed to the place of interment over planks successively placed on the ground ahead of the rollers. The vault is then raised from the rollers by means of jacks and pulleys and is deposited as required or is moved onto planks of a special lowering device positioned alongside and over the grave pit. In the latter case, the vault is raised by the special device, the planks are removed, and the vault is eased into the ground.

The procedure is clumsy, undignified, wasteful of time and labor, and damaging to lawns and general landscaping.

The invention overcomes these objections by the provision of a carriage comprising means forming an arch at either end thereof, angularly adjustable rear wheels secured to the legs of the rear arch, angularly adjustable front wheels secured to the legs of the front arch, an adjustable handle for pulling and/or steering the carriage, and mechanisms including a carrier member pivotally supported between the front and the rear arches for controlling the lowering and raising of a vault to be handled. The carriage is wheeled over the vault and the vault is suspended therein by the operation of the mechanism disposed between the arches. The vault is then wheeled to the place of interment. The angular adjustment of the wheels permits forward motion similar to the motion of ordinary vehicles, and also permits motion perpendicular to the forward movement. This feature may be required for manipulating the vault over circuitous paths through the cemetery and for positioning the vault properly over the grave pit at the place of interment.

The device may be made, for example, in accordance with the embodiment illustrated in the accompanying drawings. In these drawings,

Fig. 1 shows an embodiment of the new device in schematic perspective representation;

2

Fig. 2 is a diagrammatic section through the adjustable mounting of one of the rear wheels of the device Fig. 1;

Fig. 3 is a hood for covering the raising and lowering mechanisms of the device;

Fig. 4 illustrates a tool for angularly adjusting the rear wheels of the device Fig. 1;

Fig. 5 represents a section through the adjustable mounting of one of the front wheels;

Fig. 6 is a diagram illustrating the steering and adjustment of the front wheels of the device Fig. 1; and

Fig. 7 shows the mounting of certain tie-rods.

Referring now to the drawings, the new device comprises an angular member forming an arch at the rear end, having the upright legs 11 and 12. Another arch is similarly formed at the front end of the device, having the angular uprights 13 and 14. It will be seen that the uprights are made alike, and are positioned back-to-back. The angular member forming the rear arch comprises the flanges 15, 16 and the member forming the front arch comprises the flanges 17, 18.

Each arch is provided centrally at the top thereof with a slot extending through the vertically upwardly projecting flange thereof. These slots are indicated in Fig. 1 by the numerals 19 and 20, respectively. They serve for the pivotal attachment of flanged stub shafts 21 and 22 projecting from the end plates 23 and 24 of a connecting plank-like carrier and supporting member 25. On the under side of this supporting member 25 are provided angular pieces 26 and 27 forming with the downwardly depending end plates 23 and 24 bearings for receiving the shafts of two pulley drums indicated by numerals 28 and 29. Firmly attached to each of these pulley drums is one end of a cable, the free end of which is provided with a suitable hook. Thus, the cable 30 is carried by the pulley drum 28 and the cable 31 is carried by the pulley drum 29. The inwardly projecting shafts of these pulley drums carry couplings for coupling engagement with intermediate shafts 32 and 33, respectively. Shaft 32 projects inwardly into a brake structure 34, and shaft 33 projects inwardly into a motor and gear structure schematically indicated at 35. Both intermediate shafts 32 and 33 project inwardly from the brake and motor-gear structures, respectively, and unite in a coupling 36. The coupling between the shaft of pulley 28 and the intermediate shaft 32 is indicated by reference numeral 37, and the cou-

pling between the shaft of pulley 29 and the intermediate shaft 33 is indicated by numeral 38.

The motor and gear arrangement 35 may include a small motor similar to starter motors in automobiles. The motor should be of the reversible type so as to provide driving power for the pulleys 28 and 29 in either direction of rotation. A suitable gear may be provided between the drive shaft of such motor and the intermediate shaft 33 driven thereby.

The brake arrangement schematically indicated at 34 may be a suitable drum brake of either the internal or the external type, and of any suitable approved and well known structure. Its purpose is to apply brake power to the intermediate shaft 32 so as to control the lowering or lifting of the vault suspended on the hooks of the cables 30 and 31.

A storage battery 40 is provided on the under side of the supporting member 25 and is mounted by means of suitable brackets. It furnishes the current for the operation of the motor 35 to rotate the intermediate shaft 33 and thereby the pulley drums 28 and 29.

Numerals 41 indicates a hydraulic line for the operation of the brake 34, and numeral 42 indicates a suitable conduit carrying the electric conductors provided for the control of the motor-gear arrangement 35. The hydraulic line 41 may be accommodated within the conduit 42.

It will be seen from the above description and from the drawing Fig. 1 that the entire operating mechanism so far described is pivotally suspended on top of the two arches comprising the legs 11-12 and 13-14, respectively. The center of gravity, that is, the shaft axes of the pulleys 28 and 29, is below the hinge or pivot points 21 and 22, as it should be for safe and proper operation. Angular displacement of the uprights of the arch, as the device rolls over uneven ground, will not affect the operating mechanism and pulleys, and will therefore not disturb the weight supported on the cables 30 and 31, because such displacement will be taken up and compensated for by the pivotal suspension of the mechanism on the supporting arches.

A cover such as shown in Fig. 3 is provided for the control mechanism suspended from the supporting and carrier member 25. The cover is made of suitable material, e. g., sheet metal, forming a shell 75 which fits over the end plates 23, 24. Legs such as 76, 77, 78 hold the cover removably in position on the supporting and carrier member 25. Cut-outs 79-80 are provided for the cables 30 and 31, respectively.

A suitable switch, indicated in Fig. 1 at 45, is provided for controlling the operation of the motor-gear arrangement 35. The brake control includes a pivotally mounted handle 46 coacting with a suitable ratchet in the segment-shaped mounting 47. Numeral 48 indicates schematically the master cylinder of the hydraulic control for the brake 34. As noted before, the hydraulic line 41 is accommodated in the conduit 42 together with the circuit conductors leading from the switch 45 to the storage battery 40 and to the motor-gear arrangement 35, respectively.

Each leg or upright 11-12 of the rear supporting arch is provided with a wheel mounting and wheel adjusting means. The mounting and adjusting means for the upright 11 may be described with reference to Fig. 2. It comprises a bottom plate 50 firmly attached to the flanges 15 and 16 of the upright 11, for example, by welding. The plate 50 is provided with a recess for

accommodating a bearing 51. The wheel mounting comprises a cup-like member 52 having a flange 53 which is firmly attached to a plate 54, e. g., by welding. The plate 54 carries an extension 55 provided with a pair of holes 56 and 57 (see also Fig. 1) and a plurality of holes, e. g., four holes 58a, for receiving the pin 58 inserted through a hole in the flange 61. These holes 58a are angularly spaced apart in the plate 54 by 90°. Accordingly, when the pin 58 is inserted as shown in Figs. 1 and 2, the mounting is locked with the wheel 64 alongside and outside the upright 11, as shown in Fig. 1. A bolt 59 is firmly secured to the plate 54 and extends upwardly therefrom. On top of the plate 54 is disposed a cup-like member 60, the inside of which may be filled with grease, having a peripheral flange 61 and an inwardly extending flange 62 forming a recess for accommodating the bearing 63. The wheel axle carrying the wheel 64 is shown at 65. Member 60 and flange 61 may be made of one piece.

The structure is assembled by placing the flange 61 of the cup-like member 60 on the plate 54, with the bearing 63 in place, as shown, and the bolt 59 projecting upwardly therefrom for insertion through the plate 50 at the lower end of the upright 11. A suitable washer is placed on the bearing 51 in plate 50. The assembly is secured by means of the nut 66 and cotter pin 67. Locking means, e. g., a suitable pin, may be provided to prevent inadvertent angular displacement of the cup-like member 60 with respect to the plate 50.

It will be seen from the above description of the wheel attachment and wheel adjustment means that the wheel 64 may be placed in two principal positions: (1) into the forward position, as shown in the drawing Fig. 1, for travel in forward direction in parallel with the longitudinal axis of the device; and (2) perpendicular to the longitudinal axis of the device. In the first case, the wheel may be positioned either outside the upright 11, as shown in Fig. 1, or inside the upright; and in the latter case, the wheel may be positioned either in front or in back of the upright. The wheel 70 for the upright 12 of the rear arch is provided with mounting and adjusting means just as the wheel 64. The device is shown in Fig. 1 with the wheels in parallel with the longitudinal axis and outside of the uprights 11 and 12.

Now, when it is desired to obtain an angular adjustment of the rear wheels for travel in a direction perpendicular to the longitudinal axis, all that is necessary is to take the tool shown in Fig. 4, comprising a handle 71 and prongs 72, 73, and to adjust each rear wheel as desired. This is done in case of wheel 64 by inserting the prongs 72-73 of the tool into the holes 56, 57 in the extension 55 of the plate 54, removing the locking pin 58 and rotating the plate 54, and therewith the wheel 64, by 90°, so that it is positioned for travel perpendicular to the longitudinal axis of the device. The wheel may be rotated for this purpose either in clockwise or in counter-clockwise direction, when looking perpendicularly downwardly upon the structure. A 90° rotation in either direction disposes a hole in the plate 54, such as the hole 58a, in alignment with the locking hole in the flange 61 and after inserting the pin 58 into the aligned holes, the wheel is locked in its alternate position either in front or in back of the upright, depending on the direction of rotation of the plate 54. The wheel 70 carried by the upright 12 may be adjusted similarly. It is thus possible to dispose the wheels 64 and 70 at right angle to

the direction of forward travel either in front or in back of the uprights 11 and 12.

The angular adjustment of the wheels for travel perpendicular to the longitudinal axis of the device is desired for sideways motion, for example, from a forward direction of travel along a row of graves, sideways across graves, for the purpose of positioning the vault hanging on the hooks attached to cables 30 and 31 over a particular grave pit.

The mounting and adjusting means for the front wheels 85 and 86 are alike and may be described with reference to Fig. 5 showing the mounting for wheel 85 at the bottom of upright 13. The mounting corresponds generally to that of the rear wheels, as previously described. It comprises a plate 87 attached to the flanges 17 and 18 of the upright, e. g., by welding. The plate 87 is provided with a recess for receiving the bearing 88. Underneath the plate 87 is a cup-like housing 89 having a peripheral flange 90 and an inwardly extending flange or partition 91 forming a recess for the reception of a bearing 92. The latter is in journal engagement with the plate 93, and attached to this plate and downwardly depending therefrom is the housing 94. Numeral 95 indicates the shaft or axle for the wheel 85. The structure is secured together by the bolt 96 which is fixedly attached to the plate 93 and extends upwardly through the plate 87 carried by the upright 13. Numeral 97 indicates a nut and 98 is a cotter pin. The various parts of the structure correspond to like parts in the mounting for the rear wheels described in connection with Fig. 2. The front wheels 85 and 86 are therefore also adjustable at an angle to the forward direction of travel. This adjustment is, of course, required in the front wheels for the purpose of traveling around curves and the like.

Each of the axle housings of the front wheels, such as the housing 94 of wheel 85, is provided with brackets 100 for rotatably mounting the arms 101, 102 of the handle as shown in Figs. 1 and 5. The arms 101 and 102 are provided with a yoke 103 which is pivotally mounted thereon at 104, 105. The arms 101 and 102 are crimped as shown in Fig. 1 so as to clear the wheel mountings when the handle is placed in normal position nestling in the uprights 13 and 14 of the front arch. This feature is desirable for storage of the device.

Tie rods 110 and 111 are provided for securing the uprights 11-12 and 13-14, respectively. Each of the tie rods is inserted, at its end, into an opening such as shown in Fig. 7 at 112, and is secured by a nut such as 113 attached thereto. Tightening of the nuts at opposite ends of each tie rod draws the corresponding uprights of the two arches together and secures their proper relative positions. Additional cross ties may be provided if desired or necessary.

The operation of the handle during normal forward travel of the device is sufficiently clear from the drawings and from the foregoing explanations. The device is simply pulled forward and curves are negotiated in usual manner, the front wheel mountings taking care of such angular displacement as may be required.

If it is necessary to dispose the device for travel in a direction perpendicular to the forward direction, the rear wheels are angularly adjusted, as previously described, and the corresponding adjustment of the front wheels is obtained by manipulating the handle in the direction of intended travel, e. g., 90° from the direction of for-

ward travel. This case is illustrated in Fig. 6 which shows in full lines the position of the handle and the front wheels for forward travel, and in dot-dash lines the position of the parts for sideways travel. The figure also explains the reasons for hingedly mounting the yoke 103 of the handle on the arms 101 and 102 thereof.

It will be observed that the operating mechanism suspended between the arches is arranged in definite sections, each of which may be separately removed for repair or adjustment and then be put in place again. Thus, the brake structure 34 may be taken out by release of the couplings 37 and 38. Likewise, the motor-gear structure 35 may be taken out separately by release of the couplings 36 and 38. The pulley 28 is separately supported in the depending bracket members 23 and 26, and the pulley 29 is similarly separately supported in the depending bracket members 27 and 24.

The device is also equipped with a coupling 128 which is attached to the main drive shaft and projects from the device through the end member 24. This coupling is provided for permitting manual raising and lowering operation by means of a suitable crank.

Detents coacting with suitable ratchets may be used in place of the brake arrangement 34 or in addition thereto. One pair of detents is in such a case preferably attached to the bracket member 26 and a corresponding pair of detents is attached to the bracket member 27 for coaction with associated ratchets on the shafts of the pulleys 28 and 29, respectively. Each of the pulleys is then separately safeguarded in either direction of rotation. The detents may be operated manually or by means of a suitable lever arrangement, one for operating the detents for pulley 28 and one for operating the detents of pulley 29.

The wheels may be provided with suitable individual brakes, if desired. Operating means for such brakes may be provided wherever desired. Such operating means may correspond to commonly known practice.

The use and operation of the device will be clear from the foregoing description, but may be briefly summarized below.

The device may be put in storage with the arms 101, 102 and yoke 103 of the handle in upright position neatly nested in the arch comprising the angular uprights 13-14. A suitable latch may be provided for keeping the handle in stored-away position.

The entire machine is easily taken apart, requiring nothing more than uncoupling the conductors in conduit 42, also the hydraulic line 44, from the connection with the switch 45 and with the brake control 46-47-48, respectively, whereupon the mounting or carrier member 25 with the entire operating mechanism can be lifted from pivotal engagement with the slots 19-20 of the supporting arches. The tie rods 110-111 may be removed and the uprights with their wheels may then be stored away. These considerations will mainly concern manufacture, shipping and storage of the device. Assembly of the device is similarly facilitated, as it requires merely hooking into position the operating mechanism by means of the stub shafts 21-22 and attachment of the tie rods 110-111. The device is ready for use upon connecting the various conductors and conduits to the motor and the brake. Suitable plug and socket joints may be provided. The servicing of the wheel mounting

70
75

and adjusting means is likewise simple. Access may be had to the bearings by releasing in each case a single nut. A protective device, e. g., a radially split cupped washer may be provided on top of each wheel mounting to prevent ingress of dirt into the bearings.

In operation the device is rolled from its place of storage by means of the handle placed in the position shown in Fig. 1 and is rolled over the vault that is to be handled. The approach may be in forward direction with the arches straddling the vault. The handle is similarly arched to permit such operation. The tie rods 110 and 111 are disposed a sufficient distance from the ground to permit placing the device over the vault by approach from the side. The switch 45 is then actuated to operate the reversible motor 35 to lower the cables 30 and 31. Alternatively, a suitable crank is used, inserted into the coupling 123 and the lowering is done manually. In the event that detents, as previously described, are provided, the proper detents for the lowering operation have to be put into operative engagement with their associated ratchets. The hooks carried by the cables 30-31 are then inserted into lifting eyelets provided on the vault or are hooked into cables attached to the vault, the latter operation being necessary in case of vaults which are not provided with lifting eyelets. The pulleys provided with the cables 30-31 are then operated in reverse direction either by actuating the switch 45 in the proper direction of operation of the motor-gear 35, or by manual operation by means of the crank attached to the coupling 120. The brake lever 46 is operated during the raising of the vault to prevent any undesired slipping. Prior to raising the vault attached to the hooks on the cables 30-31 it will be necessary to put the detents, if such are used, in proper operating position with respect to their ratchets. The vault is then lifted from the ground and the device is ready for transporting it to the place of interment. The vault is maintained in suspended position within the device either by the brake, with the brake lever locked in operated position, or by the detents, if such are used, or by both.

If it should be necessary at any place on the way to the place of interment, or at the place of interment, to change the angular position of the wheels perpendicular to the longitudinal axis of the device, which may be desirable, e. g., for positioning the vault over a certain grave pit, this is easily accomplished by use of the tool shown in Fig. 4 in a manner previously described with respect to the rear wheels. No special angular adjustment is required for the front wheels. The yoke of the handle is simply manipulated in the desired lateral direction, thus turning the front wheels either into the dot-dash position at 90° to the direction of forward travel, as shown in Fig. 6, with the wheel 85 in back of the upright 14 and the wheel 85 in front of the upright 13, or manipulating the handle laterally in the alternate position so as to dispose the wheel 86 in front of the upright 14 and the wheel 85 in back of the upright 13, whichever may be more convenient. The entire device may then be rolled sideways so as to dispose the vault over the desired spot for interment. The vault can be lowered either automatically by operating the switch 45 and coincident therewith the brake lever 46, or manually by a crank inserted into the coupling 123. Again, as in the previous case, the detents for the pulleys 28-29,

if such detents are provided, may be put into proper engagement with their corresponding ratchets. The vault may thus be lowered without any trouble, the lowering being controlled by 5 operating the brake lever 46, or by the detents, or by both.

The front wheels may be made angularly adjustable just like the rear wheels; that is to say, four holes may be provided in the plate 93, Fig. 5, 10 angularly spaced apart by 90°, for alignment with a hole in the flange 90. A locking pin such as pin 58, Figs. 1 and 2, may be inserted through the hole in the flange 90 for locking the plate 93 and therewith the corresponding front wheel in 15 any one of the four angular positions. The adjustment for sideways motion is made with the tool shown in Fig. 4, as previously described. After adjusting all the wheels, and after disconnecting the handle, the carriage is moved sideways 20 into the desired position.

It will be seen from the foregoing that the new device fully overcomes the detriments and handicaps of the previous mode of handling burial vaults. The procedure is simple and requires 25 very little effort. Use of the device reduces the time and labor to a minimum, prevents damage to lawns and landscaping, and lends the dignity to the procedure which befits operations at a cemetery.

30 The plank-like supporting and carrier member 25 may be suitably reinforced to provide the sturdiness required for handling the loads which it has to support. The two pulleys 28-29 are, as shown, positioned adjacent to and substantially 35 in line with the corresponding upright arches so that the weight of the vault is mainly carried by these arches. If desired, the structure may be modified so that the load is supported entirely by the arches. This may be done by providing a 40 sturdy rod or shaft-like member and pivotally mounting such member near its opposite ends in the slots on top of the upright arches in a similar manner as the carrier 25 is pivotally mounted on these arches, as shown in Fig. 1, and 45 providing at each end of this pivotally mounted member a pair of downwardly projecting hanger-like brackets for journalling the two pulley drums 28-29, respectively, with each pulley drum positioned so that the vertical center line of the 50 corresponding arch intersects the drum about midway. A carrier member similar to the one shown in Fig. 1 at 25 is also provided in this case for carrying the motor, the brake, the battery and auxiliary parts. This carrier member may 55 be supported by suitable hanger-like brackets connected with the pivotally mounted rod and depending therefrom. The drum shafts may be interconnected with the intermediate shaft substantially as described in connection with the embodiment Fig. 1. The load stresses are, in 60 such a structure, directly transferred to the supporting arches.

While it appears clear from the drawings, it 65 may nevertheless be emphasized that the described arrangement permits wheeling of the carriage device over a vault either by backing up, or by wheeling in forward direction, or by approach from either side of the vault. The wheels may be adjusted for sideways motion either in 70 front or in back of the associated uprights of the arches, by providing adjustments for all wheels such as shown in connection with the rear wheels of the structure and as described in connection with the front wheels. The device is thus, within 75 certain limits, adjustable as to the length of

its wheel base, therefore adjustable as to the width of the space available for sideways motion. The same holds generally true even when using the handle for the angular positioning of the front wheels, as shown in Fig. 6, although the adjustment possibilities are somewhat limited longitudinally of the device. Just which adjustment is to be used in any given case will be determined by local requirements.

The angular adjustment of the wheel mountings provides for positioning the wheels for forward travel alongside their associated uprights outside as well as inside thereof, and therefore furnishes the possibility of adjusting the spur or track width of the wheels in accordance with travel required on pathways or lanes of different width.

Caster type wheel mountings may be used if desired.

It will be seen from the foregoing description that changes and modifications may be made within the scope and spirit of the appended claims.

I claim:

1. A carriage for handling burial vaults comprising a generally horizontally disposed carrier member, an arched supporting member disposed at either end of said carrier member, a recess formed in each arched support substantially at the apex thereof for pivotally removably mounting therein the ends of said carrier member, a plurality of bracketlike members carried by said carrier member and downwardly depending therefrom at longitudinally spaced intervals thereof, operating means carried by said bracketlike extensions, and means for actuating said operating means to manipulate a burial vault with respect to the ground.

2. The structure and combination defined in claim 1, wherein said operating means comprises a plurality of axially aligned separate shaft sections journaled in said bracketlike extensions, said sections including a pair of intermediate sections and a pair of end sections, a pulley drum operated by each end section, each pulley drum having a cable attached thereto for manipulating said burial vault, a power drive for one of said intermediate sections, brake means for the other intermediate section, and means for coupling said shaft sections.

3. A carriage for handling burial vaults comprising a generally horizontally disposed carrier member, a plurality of bracketlike extensions carried by said carrier member and downwardly depending therefrom at longitudinally spaced intervals thereof, an arched supporting member disposed at either end of said carrier member, means for pivotally removably mounting each end of said carrier member on its associated arched supporting member substantially at the apex thereof, operating means supported by said bracketlike extensions, said operating means comprising a rotatable shaft journaled in said extensions, said shaft being disposed below and extending in parallel with said carrier member, a pair of pulley drums on said shaft, one at either end thereof, each pulley drum having a cable attached thereto for manipulating said burial vault, and drive means for rotating said shaft to operate said pulley drums, said drive means comprising a power drive, said shaft projecting beyond the carrier member at one end thereof for engagement with a suitable crank adapted to rotate said shaft manually instead of by said power drive.

4. A carriage for handling burial vaults comprising a generally horizontally disposed carrier member, a plurality of bracketlike extensions carried by said carrier member and downwardly depending therefrom at longitudinally spaced intervals thereof, an arched supporting member disposed at either end of said carrier member, means for pivotally removably mounting each end of said carrier member on its associated arched supporting member substantially at the apex thereof, operating means supported by said bracketlike extensions, said operating means comprising a plurality of longitudinally axially aligned shaft sections journaled in said extensions, coupling means disposed between adjacent shaft sections, a pulley drum associated with each terminal shaft section, a power drive and brake means, respectively, associated with intermediate shaft sections, said power drive and said brake means being separately mounted on said carrier member.

5. A carriage for handling burial vaults comprising a generally horizontally disposed carrier member, an inverted generally U-shaped member forming an arched supporting member disposed at either end of said carrier member, means for pivotally removably mounting each end of said carrier member on its associated arched supporting member substantially at the apex thereof, operating means carried by said carrier member and downwardly depending therefrom, a wheel secured to the free end of each of the legs of said arched supporting member and being angularly adjustable with respect thereto, a handle associated with the pair of wheels secured to the legs of one of said arched supporting members, said handle comprising a pair of pivotally mounted arms, a yoke pivotally connected with such arms, and means for actuating said operating means to manipulate a burial vault with respect to the ground.

6. A carriage for handling burial vaults comprising an arched support in the rear and an identical arched support in front, each arched support being generally in the shape of an inverted U forming two legs, a wheel pivotally secured to the free end of each leg, means for angularly individually adjusting the wheels on the legs of the arched rear support for forward travel or for travel at an angle thereto, and a device for effecting common angular adjustment of the wheels on the legs of the arched front support, said device comprising an arm pivotally secured in engagement with the pivotal mounting of each front wheel, and a member forming a yoke pivotally connected with the free ends of said arms.

7. A carriage for handling loads such as burial vaults comprising a front support having two legs each carrying a pivotally mounted wheel and a rear support having two legs each carrying a pivotally mounted wheel, means for handling the load extending between said front and said rear supports, means for individually angularly adjusting the rear wheels for forward travel or for travel at an angle thereto, and a device for effecting common angular adjustment of the front wheels, said device comprising an arm pivotally secured in engagement with the mounting of each front wheel, and a yoke member pivotally connected with the free ends of said arms.

8. A knockdown carriage for handling a heavy load such as a burial vault comprising means forming an arched front and an arched rear sup-

port, respectively, each support having two generally vertically disposed legs each carrying an angularly adjustable wheel at the free end thereof, means forming an elongated carrier for supporting said load, a journal member disposed at each end of said carrier for removable pivotal journal engagement with associated journal means carried by said front and rear supports, respectively, substantially at the apex thereof, for pivotally suspending said carrier on said supports to form a removable connecting structure therebetween which depends therefrom, a handle associated with the wheels carried by the legs of said front support, said handle comprising two arms, one pivotally connected with each wheel, and an arched yoke pivotally connected with said arms, the shape of said handle formed by said arms and said yoke conforming substantially to the shape of said arched front support.
